(57) **CLAIM**

The ornamental design for a LED light incense holder, as
shown and described.

DESCRIPTION

FIG. 1 is a front perspective view of a LED light incense
holder showing my new design;

FIG. 2 is a front elevational view thereof (rear elevational
view is a mirror image of the front elevational view without
the block plug portion);

FIG. 3 is a left side elevational view thereof (right side eleva-
tional view is a mirror image of left side elevational view);
FIG. 4 is a top plan view thereof; and,

FIG. 5 is a bottom plan view thereof.
The broken lines showing in FIGS. 1-5 are for environmental
purposes only and form no part of the claimed design.
